TENSIONING DEVICE FOR KNITTING MACHINES

Vaughn Butler, Harriman, Tenn., assignor to
Burlington Mills Corporation, Greensboro,
N. C., a corporation of Delaware

Application December 24, 1949, Serial No. 134,917

2 Claims. (Cl. 66—149)

1

This invention comprises improvements in a tensioning device for use in tensioning the fabric being knitted on a circular or spiral knitting machine.

The general object of this invention is to improve the stitch formation in the knitting of circular fabrics and particularly ladies' hose from synthetic yarns such as nylon.

An object of this invention is the provision of a structurally simple and easily usable tensioning device for the purpose of effecting uniform loop formation in the knitting of circular knit fabrics, and more specifically for eliminating streaks in circular knit ladies' hose from synthetic yarns to insure the elimination of streaks in the fabric.

Other and more detailed objects of this invention will be apparent from the following description of the embodiment thereof illustrated in the accompanying drawings. In the accompanying drawings,

Figure 1 is a somewhat diagrammatic and perspective view illustrating the manner in which the device of this invention acts to tension circular knit fabric during the knitting thereof;

Figure 2 is a side elevational view of the tensioning device;

Figure 3 is a similar view taken at right angles to the view of Figure 2;

Figure 4 is a fragmentary, vertical, central, cross-sectional view with some parts broken away showing the bearing detail of the tensioning device; and

Figure 5 is a cross-sectional, fragmentary view taken on the line 5—5 of Figure 3, looking in the direction of the arrows.

In the knitting of seamless hosiery from synthetic yarns such as nylon there is a tendency to the formation of streaks in the fabric, the elimination of which has been a difficulty not heretofore successfully overcome. The object of the invention herein disclosed is to provide a simple and practical device by means of which the formation of such streaks is eliminated.

In accordance with this invention, streak elimination is effected by tensioning the circularly knit fabric during the knitting of the courses thereof by the application of a suitably constructed weighted device to the free end of the fabric so that it is drawn off along the axis of the needle cylinder under tension as it is formed. More specifically this device effects streak elimination by insuring a uniform stitch formation as knitting proceeds.

The knitting of a circular fabric, and especially

ladies' hosiery on a circular knitting machine from synthetic yarns which are wire-like in nature, inherently tends to produce a loop formation which to the eye imparts a streaked appearance to the fabric. Synthetic yarns such as nylon are naturally resilient and have a low coefficient of friction so that the bearing of the nylon thread on itself as the result of the interconnected loop formations offers no effective resistance to hold the loops in uniform configuration. In circular knitting with latch needles it is difficult to obtain uniform stitch or loop formation due to the resilient nature of the yarn and its low co-efficient of friction. This tendency to non-uniform loop configuration is also contributed to by the fact that the needles and the sinkers tend to wear in use, imparting a looseness to the mechanical structure which permits the yarn by reason of these inherent characteristics to deviate, although minutely, from the desired loop uniformity. Even though this deviation is minute in character, it is enough in the completed fabric to cause streaks which are classed as undesirable. By properly tensioning the fabric as it is knit all these causes of non-uniformity of loop formation are held to a minimum. The prime purpose of this invention is to provide a practical device for imparting such tension to the fabric.

Referring to the drawings, the device itself is shown as comprising a body 10 of sufficient weight for the purpose. The configuration of this body is not critical, but for obvious reasons the spherical form illustrated is preferable. The sphere 10 has a diametral passage 11 extending therethrough, one terminal end of which is threaded to receive the screw threaded ends 12 of a bearing stud 13. The bearing stud 13 is concentrically telescoped within an annular recess in a sleeve 14. Interposed between the stud 13 and the sleeve 14 is an anti-friction bearing such as the ball bearing 15. It will be recognized that this ball bearing structure is diagrammatically illustrated and may be varied in detail in accordance with well known practices in the anti-friction bearing art. The sleeve or casing 14 has an integral concentric boss 16 on the upper face thereof having a central passage therethrough, the upper end of which is threaded. This serves to provide a simple method of attaching a yoke 18 to the cage 14 by means of a machine screw 17, as clearly illustrated in Figure 4.

The yoke 18 consists of an integral central portion having a pair of divergent arms having their 55 terminal ends 19 (see Fig. 5) bent inwardly in

opposed relation. As is clear from Figures 3 and 5, the terminal ends 19 are transversely grooved so as to be of similar configuration to the interior of a cylindrical spring pressed clamp 20. This clamp is in the form of a longitudinally split tube, as is clear from Figure 3. Quite obviously if the yoke 18 is made of spring metal the divergent arms can be separated to permit easy attachment and detachment of the tubular spring 20 thereto.

The tubular spring forms part of a clip or clamp consisting of a pair of plates 21 curved along their upper edges towards each other to provide a clamping jaw. The lower outside edges of the plates 21 are bent inwardly towards each other and then downwardly in more or less parallel relation, as shown in Figure 2, to form pairs of pivot lugs 22 between each pair of which lies a pivot ball 25 which is maintained in proper pivotal relation with the plates by reason of the formation in each of the tips 22 of the plates opposed depressions 23. These pairs of opposed depressions form seats for engaging the pivot balls on opposite sides thereof. The central portions of the plates 21 have downward extensions 24 forming finger pieces by means of which the clamps may have opened against resistance of the tubular spring 20.

It will be readily seen from the above description that the upper opposed clamping edges of the plates 22 can be separated by pressure on the extensions 24 from opposite sides against the resistance of the spring 30 so that the edge of the tubular knit fabric F can be gripped therebetween.

The manner in which this device is used will be clear from Figure 1. The needles of a circular or spiral knitting machine are diagrammatically illustrated at N in this figure and as lying at the upper end of the knitting machine cylinder C down through which the tubular fabric F progresses as its length increases. In the use of this device in the knitting of ladies' hosiery when the welt is completed the machine is stopped either manually or automatically and the knitting machine head is raised. The operator then reaches down into the cylinder C and pulls the knitted welt back up through the needles so that the free end of the welt extends upwardly. The tensioning device of this invention is then passed downwardly through the open upstanding end of the welt and the edges of the welt are folded inwardly and positioned between the clamping jaws of the plate 21, which of course have been opened by pinching on the extensions 24. The clamp is then released so that it attaches itself to the free or beginning end of the welt, and the device is then lowered back down through the cylinder C so that it is held suspended by the welt. The machine is started up and as the boot, in the case of a ladies' stocking, is knit the fabric will be drawn downwardly under the tension of the weight of the device. In one practical form for use on commonly used circular knitting machines the total weight of the device may be of the order of three-quarters of a pound. Due to the tension in the fabric caused by the weight of

the device, a more uniform stitch is formed and once properly formed remains thus due to this tension in the fabric caused by the device suspended thereby.

- 5 The anti-friction connection between the weighted body 10 and the supporting structure therefor is provided to keep the fabric being knit from twisting when the machine is started and when the cylinder of the machine is oscillating during the production of the heel and toe. The 10 inertia of the body 10 with the anti-friction support therefor prevents that body from tending to rotate, with the result that the fabric being knitted is not twisted as an incident to the normal 15 operation of machines of this type. When the knitting of the fabric has been completed the tension device can easily be detached by again applying pressure to the tension or finger pieces 24, which opens the clamp jaws.
- 20 As will be obvious to those skilled in the art, this tension device acts throughout the knitting of the fabric to impart a constant and uniform tension thereto. It will be appreciated that the utility of this device is increased by reason of the 25 fact that it may be used in conjunction with circular knitting machines commonly used today without requiring other than the conventional manner of operation of the machines. The weight may be quickly attached at the proper 30 time so that the idle time of the machine by reason of the use of the device is of very short duration.
- 35 Those skilled in this art will readily appreciate that variations in the details of construction and 40 use of this device may be practiced without departing essentially from the construction illustrated herein, and I do not, therefore, desire to be strictly limited to the particular embodiment selected for illustrative purposes, but rather to the scope of claims granted me.

What is claimed is:

1. A tensioning device of the type described comprising a body of predetermined weight, a stud shaft secured to said body, a bearing cage disposed concentrically with said stud shaft, an anti-friction bearing interposed between said stud shaft and cage, and a clamp secured to said cage.
- 45 2. In the combination of claim 1, said clamp including a pair of pivotally interconnected spring pressed clamping members and a yoke for attaching said clamping members to said cage.
